Philip Farnsworth

UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT. A CORPORATION OF CONNECTICUT.

DIES FOR TRIMMING BLANKS.

1,321,962.

Specification of Letters Patent.

Patented Nov. 18, 1919.

Application filed November 7, 1918. Serial No. 261,541.

To all whom it may concern:

Be it known that I, RICHARD LESTER WILCOX, a citizen of the United States, and a resident of Waterbury, county of New Haven, 5 State of Connecticut, have invented certain new and useful Improvements in Dies for Trimming Blanks, of which the following is a specification.

My present invention relates to improvements in dies for giving a trimmed cross-section to a blank as is done, for instance, in forming the square, hexagonal or octagonal shapes of bolt heads, nuts, and the like, or a many sided shape of any kind 10 such, for instance, as a circular section with flat sides as is formed on shackle bolts and the like. It will be understood that by "polygon" or "polygonal" I mean any such shape. A blank may also be cut so as to 15 have a circular section.

One of the objects of my invention, among others, is to produce a series of dies arranged to work successively on a blank which will be easy to construct and to sharpen and at 20 the same time will enable any polygonal shape to be trimmed by successive cuttings without the dies becoming clogged with 25 chips.

With this and other objects in view, my 30 invention consists of the construction and arrangement hereinafter described and pointed out in the appended claims.

In the accompanying drawings, Figure 1 is a perspective view of a form of die which 35 I have adopted for illustrative purposes, and which would normally be used as the "first" die, that is the one into which the blank is passed first.

Fig. 2 is a second die arranged to coöperate with the die shown in Fig. 1.

Fig. 3 is a vertical section on 3—3, Fig. 4, through the dies shown in Fig. 1 and Fig. 2 when placed in coöperative position.

Fig. 4 is a plan view of the dies shown in 45 Figs. 1 and 2.

The corresponding parts are referred to both in the drawings and the specification by similar reference characters.

In the first die 10, shown in Fig. 1, there 50 is an opening 11 extending therethrough, the top surface of the die being conical in the form illustrated as at 12, and provided with a series of surfaces 13 preferably but not necessarily flat, which intersect opening 11

in such a way as to form cutting edges 55 around the periphery of opening 11.

In Fig. 2 is shown a second die 14 which is also provided with an opening 15 therethrough and surfaces 16 on a conical top portion 17, these surfaces being preferably, 60 though not necessarily, flat. The opening 15 is smaller than the opening 11.

In operation, dies 10 and 14 are superimposed on each other, as best shown in Fig. 3, and to this end the base of die 10 is preferably provided with a conical recess adapted 65 to fit over the conical surface 17 of die 14. As shown in Fig. 3, openings 11 and 15 are in alinement with each cutting edge of one die substantially in the same plane as one 70 of the cutting edges of the other die.

As will be seen by an inspection of Fig. 3, the chips formed by the cutting edges on die 10 will readily slide down the top surface of the die or down the surfaces 13 away 75 from the cutting edge. Similarly these chips would tend to slide down the surfaces 16 of the die 14 but, in practice, this opening is insufficient so that preferably I provide supplemental recesses 18 in the bottom 80 of the die 10 which, by being positioned in proper relation to the surface 16, provide a relatively large opening. Thus chips formed by the cutting edges on die 14 may readily pass to the exterior of the dies to prevent 85 the cutting edges becoming clogged.

It will be understood that the cutting edges of each of the dies may be readily sharpened by grinding the surfaces 13 and 16. It will also be understood that the cutting surfaces on the dies may be formed in any suitable manner other than by means of the surfaces 13 and 16, as illustrated. 90

It will be also understood that while I have shown only two dies in coöperative relation, as many of such dies may be placed end to end as desired, so that the successive chips cut from the blank as it is passed through the openings 11, 15 and the like may be relatively small for the total amount 100 of metal to be removed, each die cutting only a small portion of this total. In such case, the additional dies would be preferably of the form shown in Fig. 1, each having a conical top surface and a conical recess to 105 fit over the top surface of the die next below it. It will also be understood that, for some purposes, the top surface of the dies may

be other than conical and, indeed, may be flat, provided that the cutting edges of the dies below the first die are formed by surfaces such as 16.

5 While I have shown the illustrated form of dies as of the solid type, it will be understood that such die may be also formed by building up sections of steel, if desired.

I claim—

10 1. A pair of dies, each having an opening therethrough, one opening being slightly smaller than the other, with cutting edges forming the periphery of one end of each opening, the dies being positioned together with the openings in alinement and with each cutting edge on one die in substantially the same plane as a cutting edge on the other die, the base of the first die resting against the top of the second die and the 20 base of the first die having openings extending from the cutting edges of the second die to the exterior of the dies.

2. A pair of dies, each having an opening therethrough, one opening being slightly 25 smaller than the other, with cutting edges forming the periphery of one end of each opening, the dies being positioned together with the openings in alinement and with each cutting edge on one die in substantially 30 the same plane as a cutting edge on the other die, the top of the second die being conical and contacting with a conical recess in the base of the first die, the base of the first die having openings extending from the cutting 35 edges of the second die to the exterior of the dies.

3. A pair of dies, each having an opening therethrough, one opening being slightly smaller than the other, the top of the second 40 die being conical and contacting with a conical recess in the base of the first die, the second die having a plurality of substantially 45 flat surfaces on its top face, the planes of such surfaces making acute angles with the axis of the opening in the die and intersecting the edges of the opening to form a series of cutting edges in the periphery thereof, the first die having a series of cutting edges around the periphery of its opening 50 and the two dies being positioned so that

the openings therethrough are in alinement, with each cutting edge of one die in substantially the same plane as a cutting edge on the other die, the base of the first die having a plurality of openings extending from the cutting edges of the second die to the exterior of the dies and each adjacent one of the flat faces on the second die.

4. A pair of dies, each having an opening therethrough, one opening being slightly 60 smaller than the other, with cutting edges forming the periphery of one end of each opening, the dies being positioned together with the openings in alinement and with each cutting edge on one die in substantially 65 the same plane as a cutting edge on the other die, the base of the first die resting against the top of the second die, the dies being provided with openings extending from the cutting edges of the second die to the exterior 70 of the dies.

5. A pair of dies, each having an opening therethrough, one opening being slightly 75 smaller than the other, with cutting edges forming the periphery of one end of each opening, the dies being positioned together with the openings in alinement and with each cutting edge on one die in substantially 80 the same plane as a cutting edge on the other die, the top of the second die being conical and contacting with a conical recess in the base of the first die, the dies being provided with openings extending from the cutting edges of the second die to the exterior 85 of the dies.

6. A die to be used with a second die having an opening therethrough and cutting edges forming the periphery of the opening, and a plurality of recesses in the base of the die extending from the opening to the exterior of the die.

7. A die to be used with a second die having an opening therethrough and cutting edges forming the periphery of the opening, the base of the die having a conical recess 95 and a plurality of recesses in such conical surface extending from the opening to the exterior of the die.

RICHARD LESTER WILCOX.
